[57] **CLAIM**

The ornamental design for a trim piece for an office furniture system, as shown and described.

DESCRIPTION

FIG. 1 is a perspective view of a trim piece for an office furniture system showing our new design;

FIG. 2 is a left side elevational view thereof, the right side being a mirror image thereof;

FIG. 3 is a top plan view thereof;

FIG. 4 is a front elevational view thereof, the rear view being a mirror image thereof;

FIG. 5 is a bottom plan view thereof;

FIG. 6 is a perspective view of an alternate embodiment of our new design;

FIG. 7 is a left side elevational view thereof, the right side being a mirror image thereof;

FIG. 8 is a top plan view thereof;

FIG. 9 is a front elevational view thereof, the rear view being a mirror image thereof; and,

FIG. 10 is a bottom plan view thereof.

The trim piece for an office furniture system has been broken in the center to indicate indeterminate length.

The phantom lines depicted in FIGS. 1 and 6 are for more clearly illustrating the environment in which the trim piece is used. The phantom lines are for illustrative purposes only and form no part of the design.
